JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

AUTOMOBILE SWITCH-LOCK.

1,303,825.

Specification of Letters Patent. Patented May 13, 1919.

Application filed November 29, 1918. Serial No. 264,572.

To all whom it may concern:

Be it known that I, JOHN H. SHAW, of the city and county of New Haven and State of Connecticut, have invented certain

5 new and useful Improvements in Automobile Switch-Locks, of which the following is a full, clear, and exact description.

This invention relates to locks and more particularly to novel means for securing a 10 pin tumbler lock in place within a receptacle or the like, in which the same is to operate, this application being a continuation in part of my earlier application, Serial No. 246,127, filed July 22, 1918.

15 The primary object of this invention is to provide a cylinder lock with means for engaging the opposite walls of a receptacle or the like in which it is mounted to thereby retain the lock in its operative position 20 within the receptacle.

Another object of my invention is to provide a cylinder lock with projections constructed to be seated in the opposite walls of a receptacle or the like, in which it is 25 mounted, whereby the means which retain said opposite walls in their spaced relation also retain the cylinder lock in place within the receptacle.

Still another object of my invention is to 30 provide a switch casing or the like having manually operable switches therein with very simple key controlled means for locking said switches so that they cannot be operated by an unauthorized person.

35 To these and other ends the invention consists in the novel features and combinations of parts to be hereinafter described and claimed.

In the accompanying drawings:

40 Fig. 1 is a front elevation of a well-known type of automobile switch casing having my improved cylinder lock mounted therein.

Fig. 2 is a sectional view of Fig. 1 taken 45 on the line 2—2 looking in the direction of the arrows.

Fig. 3 is a view of the inner face of the rear wall of the switch casing shown in Fig. 1, with my cylinder lock in its operative position.

50 Fig. 4 is a view similar to Fig. 3, but showing the cylinder lock cut by a section taken on the line 4—4 of Fig. 2.

Fig. 5 is a sectional view taken on the 55 line 5—5 of Fig. 1.

Fig. 6 is a fragmentary view of the inner face of the rear wall of the casing showing the sockets formed therein for one end of my cylinder lock, and

Figs. 7 and 8 are plan and side views respectively of my cylinder lock removed from the switch casing.

In the drawings, I have designated by the numeral 10, a well-known type of automobile switch casing, which is commonly 60 mounted upon the instrument or dash board of an automobile. This type of switch casing is commonly provided with a pair of switch levers, such as 11 and 12, by means of which the electrical switches contained 65 within the casing 10 may be turned off and on. This type of switch casing usually consists of a sheet metal plate or disk 13, which is firmly secured to a cup-shaped sheet metal member 14. These two members 70

are conveniently secured together by the rearwardly projecting post 15, which is rigidly secured to the center of the two plates just mentioned. The cup-shaped member 14 provides an inclosure in which 80

the switch elements (not shown), but operated by the switch levers 11 and 12 are housed, the rear of the switch casing being closed by a disk member 16 formed of any 85

desired insulating material, such as ebonite. The disk member or rear plate 16, fits snugly 90 within the cup shaped member 14, and is provided adjacent its outer face with the annular shoulder 17, against which the rear edge of the cup-shaped member 14 abuts. The member 16 has a drill hole formed 95

centrally therethrough to receive the rearwardly projecting post 15, which is threaded, and is provided with a threaded nut by means of which the rear plate 16 may be 100 clamped to the cup shaped member 14. The instrument or dash board (not shown) is usually provided with a cylindrical opening in which the cup-shaped member 14

may be snugly mounted, the marginal portion of the disk 13 contacts with the forward face of the instrument board and covers the opening, just mentioned. The construction 105 of the switch casing, so far described, is well known, and since it forms no part of my invention, further description is unnecessary.

The locking means which I provide for locking the switch levers 11 and 12, so that they cannot be operated, consists of a plate 110

- 18, slidably mounted in a recess 19, formed in the inner face of the member 16. This plate 18, has an elongated slot 20 formed therein to clear the rearwardly projecting 5 post 15, and is slidably retained in place upon the inner face of the member 16 by any desired means such as pins 21, which extend through elongated slots 22 formed adjacent the opposite ends of the plate 18.
- 10 In order to hold the plate 18 against accidental movement, when it has been shifted to one end of its path of movement or the other, I provide a spring operated pawl 23, which is pivotally mounted upon a pin 24, mounted 15 in the rear wall 16. The forward end of the pawl 23 is provided with a rounded nose, which engages one or the other of the notches 25 formed in an edge of the plate 18, the pawl being held in engagement with the 20 plate 18 by the spring 26. In order to provide means by which the cylinder lock hereinafter described may operate the plate 18, I form an extension 27 upon this plate, the outer end of which is bent at right angles 25 to this extension, as shown at 28 in Fig. 5 of the drawing. Since my invention relates to the construction of the lock, which operates the sliding plate 18 and does not relate to the mechanism by which the plate 18 locks the 30 switch levers 11 and 12 against movement, I have not attempted to disclose or describe the coöperating means between the plate 18 and the switch mechanism operated by the levers 11 and 12, it being obvious that any 35 preferred mechanism may be used for this purpose without in any way affecting the construction or the mounting of my cylinder lock hereinafter described, within its receptacle.
- 40 The cylinder lock which I have disclosed in the drawings consists of a lock case 29 having the usual pin tumbler extension 30 with the usual pin tumblers 31 slidably mounted therein. Rotatably mounted in the 45 lock case 29 is mounted the usual type of key barrel 32 the forward end of which projects beyond the case 29 as at 33 and is provided with the usual shoulder which engages the forward face of the case 29 in a well known 50 manner. The shoulder just mentioned prevents the key plug from sliding within the case in a rearward direction and the laterally projecting pin 34 mounted in the key plug adjacent the rear end thereof contacts 55 with the rear face of the case 29 and prevents the key plug from sliding in the opposite direction. Upon the case 29 is formed a plurality of rearwardly projecting lugs 35, two lugs being shown in the construction 60 illustrated in the drawings. These lugs, it should be noted are spaced laterally from the key plug 32, a sufficient distance to permit the outer end of the pin 34 to clear these lugs when the key plug is rotated by its 65 key 36.

The means which I provide for operatively mounting my cylinder lock within the switch casing consists in forming a drill hole through the front wall of the switch casing in order that the forwardly 70 projecting end 33 of the key plug may project through this opening, the same being constructed to form a bearing in which the head 33 rotates. The outer end of the key plug 32 is thus permitted to project through 75 the front face of the switch casing (as shown in Fig. 1) in order that the key 36 may readily be inserted in the same. In the rear wall 16 of the switch casing opposite the opening, just mentioned, is formed a pocket 80 or clearance space 37 in which the projecting pin 34 may swing when the key plug is rotated; also, if desired, a second pocket 38 may be formed in the wall 16 to clear the rearward projecting end of the key plug 32, 85 should this key plug extend some distance beyond the rear face of the case 29. In addition to the pockets just mentioned, sockets 39 (as shown in Fig. 6) are formed in the plate 16 to snugly receive the rearwardly 90 projecting lugs 35 so that when these lugs are seated in said sockets the lock case 29 is prevented from rotating. If the length of the case 29 is such that the forward face of 95 this case will abut against the inner face of the cup shaped member 14, as shown in Figs. 2 and 5, when the lugs 35 are seated in the sockets 39, it will be seen that the lock case will be firmly retained in place.

From the above description when read in 100 connection with the drawings, it will be seen that if my cylinder lock is mounted within the switch casing, with one end projecting into the opening formed in the forward wall of this casing, and with the lugs upon the 105 opposite end projecting into the sockets 39, the lock will be rigidly secured in place by the front and rear wall of the switch casing. It will also be apparent, that in the construction herein disclosed, it is unnecessary to 110 rigidly secure my cylinder lock to any element of the switch casing before the parts of the casing are assembled, for when the parts of the casing are secured in place by the nut upon the post 15, my cylinder lock will be 115 clamped between the front and rear wall of the switch casing and will be rigidly secured in place by the construction above described.

When my cylinder lock is mounted in the 120 switch casing in the manner above set forth, the sliding plate 18 may be operated by rotating the key plug 32, due to the fact that the pin 34 is so positioned that it engages either one side or the other of the bent end 125 28 formed upon the extension 27. By inserting the key 36 within its key plug and rotating the same, the pin 34 will be moved out of contact with one face of the member 28 and will be swung through substantially 130

- a complete circle to engage the opposite side of this member 28, whereupon the pin 34 will move the sliding plate 18 to the left, with respect to Fig. 4. It will thus be seen that the key plug 32 not only operates the sliding plate 18 by means of the pin 34, but also locks this plate in either its operative or inoperative position, for when the key 36 is removed from its key plug, the plug 10 is locked against rotation in a well known manner, and the pin 34 is thereby retained in the position shown in Fig. 4, in which position it prevents the plate 18 from moving in a left hand direction; and if the key plug 15 is operated by its key to move the plate 18 in a left hand direction with respect to Fig. 4, the key plug upon being rotated through a complete revolution will lock the plate 18 in its new position in the manner above 20 pointed out, as the pin 34 will then be held in engagement with the opposite side of the member 28.

Although I have disclosed my cylinder lock as mounted within an automobile switch casing, it will be apparent that the means herein disclosed for retaining my cylinder lock in place between a pair of spaced walls may be used in connection with various devices other than the automobile switch casing 30 herein shown.

What I claim is:

1. A cylinder lock having a case and projections extending from each end of said case, said projections constructed to be received in sockets formed in spaced supporting plates or the like, and thereby retain said lock in operative position between said plates or the like.
2. In a cylinder lock, a case, a key plug within said case and projecting from one end thereof, lugs upon said case and projecting from the opposite end thereof, said projecting lugs and key plug constructed to be received in sockets formed in the spaced elements between which said cylinder lock is mounted, whereby the lock is retained in its operative position between said elements.
3. In combination with an automobile switch casing having a manually operable switch therein, a key controlled lock for preventing the operation of said switch, said lock having projections extending from the opposite ends thereof and constructed to project into sockets formed in the opposite walls of the switch casing, whereby the lock is retained in operative position within said casing.
4. In combination with a switch casing having a manually operable switch therein, a cylinder lock mounted within said casing for locking said switch, said cylinder lock having projections upon its opposite ends constructed to project into the opposite walls of said casing and thereby retain said lock in its operative position.
5. In a switch casing having a manually operable switch therein, a cylinder lock mounted in said casing for locking said switch, said lock provided with a case and a key-plug rotatable therein, lugs formed upon 70 said case and constructed to project into sockets formed in one wall of said switch casing, said lugs retained in said sockets by the opposite face of said lock case engaging a second wall of said casing, whereby said cylinder lock is retained in operative position within its switch casing.
6. In combination with a switch casing having a manually operable switch therein, a cylinder lock for locking said switch, said 80 lock comprising a case having a key-plug rotatable therein, said key-plug constructed to project beyond said case into engagement with one wall of the switch casing, and lugs upon the opposite end of said lock case constructed to extend into the opposite wall of said switch casing, whereby the cylinder lock is clamped between the opposite walls of said casing and retained by said projections in operative position within said 85 switch casing.
7. In combination with a switch casing having a manually operable switch therein, a plate slidably mounted within said casing for locking said switch, a cylinder lock with- 90 in said casing comprising a lock case and key-plug, and means upon said key plug for operating said plate, said lock constructed to be clamped between the opposite walls of said switch casing, and rearwardly projecting lugs upon the lock casing constructed to extend into the rear wall of the switch casing to thereby retain the cylinder lock in place within said switch casing.
8. In combination with a receptacle having manually operable means therein, a cylinder lock within said casing for locking said means, said lock constructed to be clamped between the opposite walls of said receptacle and provided with projections extending into the opposite walls of said receptacle to thereby retain said lock in its operative position within said receptacle.
9. A pin tumbler lock having a case constructed to be clamped between the front and rear walls of a receptacle in which it is mounted, said case provided with projections constructed to extend into said walls to thereby retain said lock in place within said receptacle.
10. In combination with a cylinder lock, a supporting plate having sockets formed therein, means for retaining said lock in place upon said plate, comprising lugs upon said lock projecting into said sockets, and means engaging the opposite face of said lock for retaining said lugs in said sockets.
11. A pin tumbler lock having projections extending from the opposite ends thereof for retaining the lock in place.

12. A cylinder lock having lugs projecting from one end thereof and the key-plug projecting from the opposite end thereof for retaining said lock in place.
13. In combination with a receptacle having separate front and rear walls, a pin tumbler lock having a case within said receptacle, means projecting from the opposite ends of said case into said walls, and means for securing said walls in spaced relation, said last mentioned means serving also to secure said lock in place within said receptacle.
14. In combination with a switch casing having separate front and rear walls, a pin tumbler lock having a case within said switch casing, projections extending from said case into said walls, and means for securing said walls in their spaced relation, said last mentioned means serving also to secure said lock in place within said casing.
15. In combination with a pair of spaced mounting plates, a pin tumbler lock having a case and a key barrel, said key barrel constructed to project from said case into said plates to secure said lock in place between said plates, and means extending from said case into one of said plates to prevent relative rotation therebetween.
16. In combination with a pair of spaced mounting plates, a cylinder lock having a case and a key barrel, said key barrel having its outer end extending beyond the face of said case, said case having rearwardly projecting lugs formed thereupon, said lugs and outer end of the key barrel projecting into said plates to secure the lock in place therebetween.
17. In combination with a pair of spaced mounting plates, a cylinder lock having a case, said case having a key barrel extending therefrom in one direction and lugs extending from the case in the opposite direction, said lugs and key barrel projecting into said plates to secure the cylinder lock in place therebetween.
18. In combination with a pair of spaced mounting plates, a pin tumbler lock applied to the rear face of the forward plate and having a case and a key barrel, rearwardly projecting lugs upon said case, said rear plate having lug receiving sockets formed therein, said lugs seated in said sockets and retained therein by the forward plate against which the outer face of the lock case abuts.
19. In combination with a pair of spaced mounting plates having a drill hole in the forward plate and sockets in the rear plate, a pin tumbler lock having a case and a key barrel, rearwardly projecting lugs upon said case seated in said sockets, said key barrel having its outer end extending through said drill hole, and said spaced plates positioned to prevent said lock from moving axially therebetween, whereby said lock is retained in place.
20. In combination with a pair of spaced mounting plates, a cylinder lock having a case, means projecting from the opposite ends of said case into said plates to secure said lock in place between said plates.
21. In combination with a pair of spaced mounting plates, a cylinder lock having a case, means projecting from the opposite ends of said case into said plates to secure said lock therebetween, whereby separation of said plates releases said lock from both of said plates.
22. In combination with a pair of spaced mounting plates, a cylinder lock having a case clamped therebetween, and means projecting from the opposite ends of said case into said plates for securing said lock in place between said plates for securing said lock in place between said plates.
23. In combination with a pair of spaced mounting plates, a cylinder lock having a case clamped therebetween, means projecting from the opposite ends of said case into said plates for securing said lock in place between said plates and means slidably mounted on the rear spaced plate operated by said lock.
24. In combination with a pair of spaced mounting plates, a cylinder lock having a case mounted between said plates, said case having a key barrel projecting from one face thereof and having lugs projecting from the opposite face thereof, said projecting end of the key barrel extending through one plate and said lugs projecting into the other plate and holding the lock case in spaced relation to said last mentioned plate, whereby the cylinder lock is secured in place between said plates, and means slidably mounted on said last mentioned plate between the same and the end of the locking case, said means operated by said lock.

In witness whereof I have hereunto set my hand on the 23rd day of November, 1918.

JOHN H. SHAW.
